UNITED STATES PATENT OFFICE.

JOHN C. WRASSE, OF MISHAWAKA, INDIANA.

CIRCUIT-SWITCH.

1,123,829.

Specification of Letters Patent.

Patented Jan. 5, 1915.

Application filed October 30, 1913. Serial No. 798,171.

To all whom it may concern:

Be it known that I, JOHN C. WRASSE, citizen of the United States, residing at Mishawaka, in the county of St. Joseph and State 5 of Indiana, have invented certain new and useful Improvements in Circuit-Switches, of which the following is a specification.

This invention relates to improvements in circuit switches, and is especially adapted 10 for use in lighting circuits wherein it is desirous of preventing the flickering of the lights caused by the surge of the electric current from the irregular action of the dynamo.

15 The objects of this invention are to provide a device of this character which will be simple in construction, cheap to manufacture and effectual in use, and these objects are accomplished by the means illustrated in 20 the accompanying drawings, in which:—

Figure 1 is a vertical sectional view of the improved device showing the lighting circuit closed. Fig. 2 is a detached perspective view of the solenoid and its attached parts 25 omitting a portion of its supporting frame: and Fig. 3 is a detail perspective view of the solenoid core showing its dasher-plate secured thereto in a different position.

In all of the figures of the drawings, similar reference numerals designate like parts.

Referring to the drawing, 4 designates a closed casing provided with a removable top 5 to afford access within the casing. Secured to and supported by the sides of the 35 casing 4, is a frame which comprises a base 7, uprights 8, and a top-bar 9, and supported by the frame is a solenoid formed of the coils 10, armature 11, and core 12. Both the armature and the core are laminated and 40 are preferably U-shaped, having their legs extending into the coils, the legs of the armature passing through apertures 13 in the top-bar 9, and their connecting piece lying upon said bar. The core is vertically mov- 45 able in the coils and has suspended from its lower end the laminated contact plate 14 whose upwardly turned terminals 15 are adapted to engage the stationary contacts 16 having threaded stems 17 and secured to the 50 base 7 by the nuts 18. The upper ends of the stems 17, together with the nuts 18 and the nuts 19, form the binding posts for one end of the lighting circuit wires 20, their other ends being connected with the usual

transformer 21 which is connected to the line 55 wires 22. The coils 10 of the solenoid are also connected with the transformer 21 through the wires 23, forming an independent circuit, and it is understood that wherever the circuit wires pass through the walls 60 of the case 4 they are insulated therefrom in any suitable manner. As thus constructed, a current of electricity passing through the independent circuit energizes the solenoid, and the core 12 is drawn upwardly 65 until the terminals 15 of the contact plate 14 engage the stationary contacts 16, when the lighting circuit is closed, as shown in Fig. 1 of the drawing. To assure a perfect contact between the terminals 15 and the stationary contacts 16, the contact plate 14 is connected resiliently to the core 12 through a spring 24 which is connected at its ends by studs 25 to said plate 14 and suspended 70 at its center from the said core 12 by the studs 26. To prevent the contact between the members 15 and 16 being made with a shock, a dasher plate 27 is fixed to the lower end of the core 12 between the spring 24 and the core, and as shown in Fig. 2, said dasher 75 plate lies in parallel alignment with the spring 24 and the contact-plate 14, and together with said member is adapted to work in oil which is contained in the casing 4 and whose level is maintained above the contacting members. Thus it will be seen that a 80 circuit switch is provided whose contacting members are controlled by an oil dasher-plate, thereby preventing the closing of the contact points with a shock, and a resiliently 85 suspended contacting plate which will take up any fluctuation of the core due to the surge of the current from the irregular actions of the dynamo, such as variations in speed of the prime mover or variable resistance on the line, whereby these variations 90 will not show in the lights, and insuring a positive non-vibrating contact when the circuit is closed.

The fluctuations of the core owing to the 95 varying surge of the current, will be taken up by the buckling of the spring 24 at its center without disturbing the contact points. Furthermore it will be seen that by connecting the spring 24 at its ends and center 100 to the contact plate 14 and studs 26 of the core 12 respectively, that a slight rocking movement of the contact 12 can be had,

should one terminal 15 contact before the other due to the looseness of fit of the movable core 12 in the coils 10.

In some instances the spring 24 and the contact plate 14 can be used without the dasher plate 27, said members forming in themselves a dasher which would prevent the closing of the contact points with a shock, but for the best results the use of the plate 27 is required.

Having thus fully described the invention, what is claimed is:

1. In a device of the character described, a frame, a solenoid and stationary contacts mounted on said frame, a spring fixed at its center to the movable core of said solenoid, and a contact plate fixed to the ends of said spring, whereby said contact plate can rock independently of its inherent resiliency and

said spring buckle at its center when the surge of the current is unequal.

2. In a device of the character described, a frame, two coils mounted in the frame, an armature mounted on the top bar of the frame and provided with legs extending into the coils, a core member movable in both coils, a spring fixed at its center to the movable core, and a contact plate fixed to the ends of said spring, whereby said contact plate can rock independently of its inherent resiliency and said spring buckle at its center when the surge of the current is unequal.

In testimony whereof I affix my signature in presence of two witnesses.

JOHN C. WRASSE.
